Oliver E. Allen.

United States Patent Office.

OLIVER E. ALLEN, OF NEW YORK, N. Y.

Letters Patent No. 77,438, dated May 5, 1868.

IMPROVED CAR-SPRING.

The Schedule referred to in these Letters Patent and making part of the same.

TO ALL WHOM IT MAY CONCERN:

Be it known that I, OLIVER E. ALLEN, of the city, county, and State of New York, have invented certain new and useful Improvements in Car-Springs; and I do hereby declare the following to be a full, clear, and exact description of the same, reference being had to the accompanying drawings, making a part of this specification, in which—

Figure 1 represents an external view of the spring.

Figure 2 represents a vertical section through the same.

My invention consists in a spring of peculiar construction, which is enclosed in a metallic case, and upon which the pressure is brought by a plunger or follower entering the said case, said spring being composed substantially of a vulcanized India-rubber body, with metallic or other sufficiently strong heads or flanges, and wound around by woollen yarn, or its equivalent, so that the rubber and yarn or exterior elastic covering may contract and expand together, one aiding, protecting, and strengthening the other.

To enable others skilled in the art to make and use my invention, I will proceed to describe the same with reference to the drawings.

In fig. 2, A represents an India-rubber body, of cylindrical form, and of such length and diameter as the load it is designed to sustain may require. The rubber should, of course, be vulcanized or cured so as to maintain as nearly as possible its normal condition and form.

B B are metallic heads, which may be united to the ends, respectively, of the rubber by screws *a a*, or otherwise, so as to form a spool, on which is wound woollen yarn, C, or its equivalent, sufficient to fill or nearly fill the spool, the heads serving as guides and holders to the wound yarn.

While the rubber and exterior winding of yarn mutually sustain and strengthen each other, they jointly produce a degree of expansive power or resistance that neither, of itself, is capable of doing or even approximating. The wound rubber, it has been found by experiment, will resist some five times or more pressure without rupture than the rubber without the winding will resist. The woollen exterior also protects the rubber (it being a non-conductor of heat) from devulcanization by exposure and the sun's rays. The two substances are peculiarly constituted for joint co-operation as a spring, and for supporting and protecting each other.

The spring, constructed as above described, is placed in a case or cylinder, D, the upper end of which is closed, and the lower end open, and a rubber or other packing, e, placed against the end of the spring next the open end of the case or cylinder, said packing protecting the spring and its chamber from dust and exposure. The end of the plunger or follower E, is made to snugly fit and enter the lower end of the case, and to bear against the end of the spring therein.

In winding the yarn upon the exterior of the rubber, it may be laid regularly or irregularly, and such an amount of friction may be applied as will cause it to wind sufficiently tight.

The spring, though mainly designed for use on cars, may be used for other purposes, and as it takes the pressure upon its ends, it may be used either end up. The encasing of the spring in a metallic case, which it should neatly fill, restricts the circumferential expansion, and causes the spring to react as soon as the pressure is taken from it, the rubber carrying up into proper position the wound jacket or covering of yarn.

Having thus fully described my invention, what I claim therein as new, and desire to secure by Letters Patent, is—

1. A spool for a car or other spring, composed of an India-rubber centre, surrounded by woollen yarn or other exterior elastic covering, substantially as described.
2. I also claim a car-spring, composed of vulcanized rubber, and wound around by woollen yarn or other exterior elastic covering, and placed and used in a metallic case or exterior, substantially as herein described.

OLIVER E. ALLEN.
